UNITED STATES PATENT OFFICE

158,398

FRAME FOR SPECTACLES

Leonard Liebowitz, Brooklyn, N. Y., assignor to
Styl-Rite Optical Corporation, Brooklyn, N. Y.

Application February 12, 1947, Serial No. 136,861

Term of patent 3½ years

(Cl. D57—1)

To all whom it may concern:

Be it known that I, Leonard Liebowitz, a citizen of the United States and resident of the city and State of New York, county of Kings, have invented a new, original, and ornamental Design for a Frame for Spectacles, of which the following is a specification, reference being had to the accompanying drawings, forming part thereof.

Fig. 1 is a front elevation of a frame for spectacles embodying my design.

Fig. 2 is a top plan view, showing the essential features of the design in full lines.

My design for a frame for spectacles is characterized by the all-over massive appearance produced by the particular downwardly pointed ends where the temples are connected in combination with the specific configuration of the lens rims

having slight protuberances on the nasal side and near the bottom on the outside thereof, all as illustrated.

I claim:

The ornamental design for a frame for spectacles, substantially as shown and described.

LEONARD LIEBOWITZ.
